UNITED STATES PATENT OFFICE.

JOHN H. BENNETT, OF WORCESTER, MASSACHUSETTS.

FERRULE FOR HANDLES.

No. 901,063.

Specification of Letters Patent.

Patented Oct. 13, 1908.

Application filed June 13, 1908. Serial No. 438,402.

To all whom it may concern:

Be it known that I, JOHN H. BENNETT, a citizen of the United States, residing at Worcester, in the county of Worcester and State of Massachusetts, have invented a new and useful Improved Ferrule for Handles, of which the following is a specification, reference being made therein to the accompanying drawings.

10 This invention relates to an improved construction in metal ferrules for wooden handles such as are employed for skipping ropes, pull devices, knives, files and other similar tools; the objects of my invention being to 15 provide a simple and efficient ferrule that will not become loose and separate from the wood handle when shrinking of the wood occurs, and which will leave a circle of wood about the central opening at the end of the 20 handle.

For the attainment of these objects my invention consists in a ferrule of the peculiar construction described, and in the combination thereof with the wooden handle-body, as 25 illustrated in the accompanying drawings, wherein

Figure 1 is a perspective exterior view of the ferrule applied to a handle. Fig. 2 is a central longitudinal section of the ferrule 30 and handle body. Fig. 3 is a separate central section of the ferrule drawn on an enlarged scale. Fig. 4 is a transverse section, one half at line W and one half at line X on Fig. 3, and Fig. 5 is a top end view.

35 Referring to the drawings, B indicates the wooden handle having the central longitudinal bore or recess C, and F indicates the metal ferrule. This ferrule is press-drawn from sheet metal, and according with my invention 40 comprises a cylindrical body portion 2 that corresponds in its internal diameter with the external diameter of the cylindrical reduced end 3 of the wood handle. The outer end of the cylinder 2 is flared or enlarged for 45 a short distance, as at 4, giving an approximately conoidal upward enlargement to its interior chamber at 5. The head is offset or turned inward, forming a narrow annular end portion 6, that stands in a plane approxi- 50 mately perpendicular to the central axis, and is about one sixteenth to one eighth of an inch, more or less, in width. At the inner edge of this annular portion 6 the metal is returned inward and downward in the form 55 of a circular inwardly tapering conoidal lip 7 about one eighth of an inch, more or less,

in width, and the inner edge of said circular lip is beveled or tapered, as at 9, forming a comparatively thin or moderately sharp circular cutting edge. The bevel 9 is preferably 60 made approximately parallel with the cylinder body 2, and concentric therewith. The central opening through the circular lip 7 is of considerable greater diameter than the bore or hole C in the handle, as best shown 65 on Figs. 1, 2 and 5.

When the ferrule F and wood handle B are assembled the ferrule is driven onto the wood A until the end of the latter is approximately flush with the outer face of the annulus 6. The conoidal lip 7 is thus forced 70 into the wood, severing a narrow annular portion thereof, as at 10, and wedging or forcing the same outward into the space or chamber 5, and by contact with the annular 75 end 6 upsetting it therein in a manner to form a complete circular clench at the outer angle of the wood within the ferrule, as best shown in Fig. 2, so that the handles with ferrules thereon can be subjected to the usual 80 variations of temperature, and tumblings, and hard usages met in transportation and use, without the ferrules escaping from the handles by reason of shrinkage in the wood, or shocks occurring thereto. It will also be 85 noticed that a large annular portion of the wood at 12 is left, between the metal of the ferrule and the central bore C, so that the tang or portion of a tool when inserted therein does not necessarily rest against the ferrule. 90

I claim—

1. A ferrule constructed as described, comprising a cylindrical body outwardly enlarged at its upper end, with a circular interior chamber having a diameter greater 95 than the inner diameter of the body cylinder, the upper end of said ferrule inwardly and downwardly returned to provide an inner downwardly directed circular conoidal lip adapted for cutting into the end of a handle 100 and forcing outward an annular portion at the angle thereof into said chamber, for the purpose set forth.

2. A ferrule for the purpose set forth, comprising a cylindrical body-portion outwardly 105 enlarged at its end and having a narrow inwardly offset annular end portion integrally united with the enlarged portion at its outer periphery, said end portion provided at its inner circle with an integral downward inwardly inclined circular lip, the central 110 opening within the circle of the lip being of

greater diameter than the bore of the handle whereon the ferrule is to be used.

3. A ferrule comprising a straight body cylinder conoidally enlarged at its outer end 5 and terminating in an integral flat annulus approximately perpendicular with the axis, and having an inwardly returned sharp-edged conoidal lip integral with its inner circle, the inner bevel at the edge of said lip 10 being concentric and approximately parallel with the body cylinder.

4. The combination, substantially as described, with a wood handle having a cylindrical ferrule-receiving end and a central bore therein, of a metal ferrule comprising 15 a cylindrical body having an enlarged end with a circular interior chamber therein, a narrow annular end portion integral there-

with and provided with a circular conoidal inwardly returned lip of greater diameter 20 than the central bore, said circular lip wedging into the end of the wood near its angle and forcing outward a narrow circular portion thereof, said circular portion being upset into the chamber within the enlarged end 25 of the ferrule beneath the annular end portion and between the outer inclined surface of the lip and inner face of the circular enlargement, for the purpose set forth.

Witness my hand this 11th day of June, 30 1908.

JOHN H. BENNETT.
